UNITED STATES PATENT OFFICE.

HARRY GILLETT, OF CLEVELAND, OHIO.

COMPOSITE ROOFING.

1,044,774.

Specification of Letters Patent. Patented Nov. 19, 1912.

Application filed August 1, 1910. Serial No. 574,770.

To all whom it may concern:

Be it known that I, HARRY GILLETT, a citizen of the United States, residing at Cleveland, in the county of Cuyahoga and 5 State of Ohio, have invented a certain new and useful Improvement in Composite Roofing, of which the following is a full, clear, and exact description, reference being had to the accompanying drawings.

10 This invention relates to composite roofings; that is to say, to roofings which are built up into a continuous structure as they are laid, as distinguished from roofings which are made up in advance and are afterward laid and which, when so laid, present distinct joints between the adjacent sections.

15 The purpose of this invention is to provide a light, strong, water proof, fire proof, and durable composite roofing, which is 20 conformable to the various conditions and incidents of use; which shall be extremely convenient of application and in which the fastening means for the lowermost layers will be effectively protected and without the 25 use of slag or gravel coating.

A further object of the invention is to 30 provide a practical composite roofing consisting largely of inorganic solid-fibered material which, while being substantially fire-proof as well as non-heat conductive, will effectually retain, with a minimum of evaporation, the water-proofing material applied thereto.

35 With the foregoing general objects in view, the invention may be defined further as consisting in the novel features of construction and the combinations of parts and elements to be hereinafter particularly described and pointed out in the claims.

40 In the accompanying drawings, Figure 1 is a fragmentary plan view of a piece of roofing constructed in accordance with my invention, the roofing being designed with special reference to a roof structure having 45 wooden sheathing, parts of the overlying layers being turned back to disclose the underlying layers and to illustrate the manner of building up the roofing; Fig. 2 represents a transverse sectional view corresponding to the line 2-2 of Fig. 1; and Fig. 3 50 an enlarged sectional detail of the sheathing and roofing.

55 Describing the various parts by reference characters, 1 denotes the foundation on which the composite roofing is laid, the

foundation herein shown being the wooden sheathing commonly employed with frame and brick constructions. To this foundation there is applied a covering consisting of a series of two-ply sheets of inorganic 60 solid-fibered material, designated generally by the reference character *a*. The two-ply sheets consist each of a lower ply 2 of unsaturated asbestos felt and an upper ply 3 of the same inorganic fibrous material which 65 has been saturated with water-proofing material, preferably asphalt, the two plies being united by means of a coating 4 of water-proof adhesive, such as asphalt, applied therebetween and the two plies being subjected to pressure to cause them to adhere 70 to each other, through said adhesive coating. The covering *a* forms a water-proof coating in which the pitch or asphalt which 75 renders the coating water-proof is kept out of contact with the sheathing by the lower 80 ply 2 and such lower ply serves as a non-conducting layer interposed between the sheathing and the water-proofed ply to keep the latter ply intact; that is to say, unaffected by changes in temperature beneath the sheathing.

The cover *a* is applied to the sheathing in courses, the lower edge of one course overlapping the upper edge of the next lower 85 course and being secured thereto by nails 5. To the covering *a* there is next applied a coating *b* of water-proof adhesive, preferably asphalt, which is mopped onto the upper surface of *a* in courses, beginning at the 90 lower end of the coating *a* and working upward. The first course will be somewhat more than half the width of the first course of the covering *a* and will be used as an adhesive for a strip 6 of saturated asbestos 95 felt, the upper edge of each course being nailed to the sheathing and through the subjacent covering *a*, as shown at 6^a in Fig. 1. The next course of water-proof adhesive covers a similar width of the covering *a* 100 and the entire surface of the strip 6. A strip 7, of the full width of the lower strip of the covering *a* is then applied to the upper surfaces of the covering *a* and the strip 6 and is rolled down into adhesive engagement therewith, the upper end of the strip 7 being secured to the sheathing by 105 nails 8. The next coating of water-proof adhesive will be of the same width as the one just described and will cover a portion 110

of the second strip of the covering *a* and the upper portion of the strip 7. This coating serves as an adhesive for the strip 7^a of saturated asbestos felt, the upper edge of which is secured to the sheathing by nails 8^a. The successive strips 7^b etc., will be applied to the sheathing and covering *a* in the same manner as the strips 7 and 7^a, namely; by means of nails 8^b and by the coating of asphalt *b*. By the application of the strips 6, 7, etc., a water-proof coating *c* is formed in which each row of nails 5, 6^a, 8, etc., is covered with at least two sheets or plies of water-proof protecting material. While utilizing nails as the means for securing the overlapping edges of the courses or sheets of the covering *a* and the upper edges of the courses or sheets of the covering *c*, the nails will be so protected as to prevent leakage and provide a roofing which will last indefinitely.

In many instances, a coating *d* of asphaltum or paint will be applied to the covering *c* to give a finished appearance to the roof. In numerous instances, however, there is a demand for a specially cool roof. In order to satisfy this demand, an adhesive coating, as asphalt, will be substituted for or may be applied to the paint, and a final coating *e* may be applied to the roofing, the final coating consisting of a series of courses or strips of two-ply material exactly similar to the first covering *a*, with the exception that the plies are reversed and that nails are dispensed with as a securing means, the courses or strips 9 being merely rolled down upon the adhesive coating 10 therebeneath, with the joints lapped, as shown at 11.

The roofing above described possesses many advantages over others with which I am familiar. The advantage of the coating of non-saturated asbestos felt adjacent to the sheathing has been set forth. The various layers or coatings of saturated asbestos felt and the manner of applying the same to the roof make leakage well nigh impossible. A great advantage which arises from the use of asbestos as the absorbing agent for the water-proofing material is that, being an inorganic solid-fibered material, there is no capillarity in the fibers themselves, the only capillarity which exists in the felt being due to the capillary spaces existing between adjacent fibers. The result is that the tendency to feed the water-proofing material to the exterior of the felt mass is reduced to a minimum, and the evaporation of the water-proofing material is correspondingly reduced.

The whole system or plan of roofing provides a roof which is extremely light, but which is of great efficiency and durability.

For convenience of description, the portion of the roof at the bottom of Fig. 1 is assumed to be the lower end or "bottom"

of the roof, the "top" of the roof being opposite the portion described but being unfinished; for the same reason, the terms "upper" and "lower" will be applied to the sheets of fabric applied to the roof, it being understood that my roofing is applicable to both flat and inclined roofs, although being intended primarily for the former type.

Having thus described my invention, what I claim is:

1. A roofing comprising overlapping sheets of fabric, the overlapping sheets being joined by an adhesive compound, each sheet nailed at its upper edge only and extending down past the center line of the next underlying sheet only a sufficient distance to also overlap the upper nailed edge of a third sheet which is similarly overlapped a second sheet, so that each nailed joint is twice overlapped, once at approximately the center line of one sheet and again by the lower edge of the next sheet above.

2. A roofing comprising overlapping sheets of fabric, the overlapping sheets being joined by an adhesive compound, each sheet nailed at its upper edge only and extending down past the center line of the next underlying sheet only a sufficient distance to also overlap the upper nailed edge of a third sheet which is similarly overlapped by a second sheet, so that each nailed joint is twice overlapped, once at approximately the center line of one sheet and again by the lower edge of the next sheet above, and an underlying foundation covering of sheets of substantially the same width as those first mentioned but having merely a single lap at the edge nailed and located under the nailed laps of the first and third above mentioned sheets.

3. A composite roof consisting of a foundation having applied thereto the following coatings:—first, a coating consisting of a series of overlapping sheets, each sheet consisting of a bottom ply of unsaturated inorganic fibrous material and an upper ply of inorganic fibrous material saturated with water-proofing material and cemented to the lower ply; second, a coating of water-proofing adhesive material; third, a coating consisting of a series of overlapping sheets of inorganic fibrous material having water-proofing material applied thereto; fourth, a coating of water-proofing adhesive material; fifth, a coating consisting of a series of overlapping sheets, each sheet consisting of a lower ply of inorganic fibrous material saturated with water-proofing and an outer ply of unsaturated inorganic fibrous material, the sheets being secured to the subjacent coating and to each other by means of water-proofing adhesive material.

4. In a roof, the combination of a foun-

dation, a covering therefor comprising a series of overlapped sheets, each sheet consisting of a bottom ply of unsaturated, fibrous, inorganic material and an upper 5 ply of fibrous inorganic material saturated with water-proofing material and cemented to the lower ply, and a plurality of plies of inorganic material secured to the upper satu-

rated plies of the two-ply foundation covering.

10

In testimony whereof, I hereunto affix my signature in the presence of two witnesses.

HARRY GILLETT.
